UNITED STATES PATENT OFFICE

114,845

DESIGN FOR A FUR CLEANING APPARATUS

Walter Haertel, Minneapolis, Minn.

Application January 26, 1938, Serial No. 74,556

Term of patent 7 years

To all whom it may concern:

Be it known that I, Walter Haertel, a citizen of the United States and residing in the city of Minneapolis, county of Hennepin, and State of Minnesota, have invented a new, original, and ornamental Design for a Fur Cleaning Apparatus, of which the following is a specification, reference being had to the accompanying drawings forming a part thereof, wherein,

Fig. 1 is a perspective view of a fur cleaning apparatus showing the front and right-hand side of my new design; and

Fig. 2 is a perspective view showing the front and left-hand side thereof.

Fig. 3 is a rear elevational view thereof on a slightly enlarged scale.

The dominant features of my design reside in the portions shown in full lines.

I claim:

The ornamental design for a fur cleaning apparatus, as shown and described.

WALTER HAERTEL.
